US00D625842S

(12) **United States Design Patent**
Mugge et al.

(10) **Patent No.:** US D625,842 S
(45) **Date of Patent:** ** Oct. 19, 2010

(54) **MOLDED SURFACE OF A CONCRETE PRODUCT**

(75) Inventors: **Jimmie L. Mugge**, Inver Grove Heights, MN (US); **Jay J. Johnson**, Star Prairie, WI (US)

(73) Assignee: **Anchor Wall Systems, Inc.**, Minnetonka, MN (US)

(**) Term: **14 Years**

(21) Appl. No.: **29/352,578**

(22) Filed: **Dec. 22, 2009**

Related U.S. Application Data

(62) Division of application No. 29/313,757, filed on Feb. 6, 2009, now Pat. No. Des. 609,367, which is a division of application No. 29/283,096, filed on Aug. 6, 2007, now Pat. No. Des. 588,714.

(57) **CLAIM**

The ornamental design for a molded surface of a concrete product, as shown and described.

DESCRIPTION

FIG. 1 is a perspective view of an embodiment of a molded surface of a concrete product, according to our new design;

FIG. 2 is a front elevational view thereof;

FIG. 3 is a right side view thereof;

FIG. 4 is a left side view thereof;

FIG. 5 is a top view thereof; and,

FIG. 6 is a bottom view thereof.

The broken lines in all views are included for the purpose of illustrating portions of the concrete product that form no part of the claimed design.
